UNITED STATES PATENT OFFICE.

CHARLES HULPIAN, OF BUFFALO, NEW YORK, ASSIGNOR TO HARD MANUFACTURING COMPANY, OF BUFFALO, NEW YORK.

BED-SPRING.

1,120,501.

Specification of Letters Patent.

Patented Dec. 8, 1914.

Application filed June 21, 1911. Serial No. 634,414.

To all whom it may concern:

Be it known that I, CHARLES HULPIAN, a citizen of the United States, residing at Buffalo, in the county of Erie and State of New York, have invented a new and useful Improvement in Bed-Springs, of which the following is a specification.

This invention relates to improvements in bed springs which are intended for use in iron and wooden beds and are adapted to be supported from the side or end rails thereof.

The object of this invention is to provide a bed spring of this kind with simple and inexpensive supporting means which are adapted to engage the side or end rails of the bed and which can be easily adjusted to increase or diminish the width or length of the bed spring, so that the latter can be readily fitted to beds of different sizes and secured in place therein.

In the accompanying drawings: Figure 1 is a fragmentary plan view of a bed spring embodying the invention. Fig. 2 is a fragmentary perspective view thereof with the springs removed. Fig. 3 is a fragmentary end elevation thereof on an enlarged scale.

Like reference characters refer to the like parts in the several figures.

The bed spring shown, in its general construction, is of usual type and comprises a supporting frame A composed of a plurality of transverse slats *a* which are connected together by cross bars *a'* to form the frame, and a plurality of upright coiled springs B which rest upon and are secured at their lower ends to the transverse slats and are connected together at their upper ends by longitudinal and transversely extending wires *b* which retain them in their upright position. These parts may all be of any suitable construction and arrangement.

The present invention relates only to the means which are employed for supporting the bed spring in position in the frame of the bed and which are constructed as follows: The supporting frame A is provided at its opposite side edges with supporting arms C which are pivoted thereto, so as to turn or swing in a plane substantially parallel with the plane of the frame. In frames where transverse slats are employed, as shown in the drawings, the arms C are preferably pivoted to the opposite ends of these slats. In these frames the slats are

formed of angle iron and are arranged with their upper flanges extending in the plane of the frame A and the supporting arms C rest upon and are pivoted to the upper faces of these flanges, so as to turn or swing in this same plane. Any other suitable means, however, may be employed for pivotally securing the arms C to the frame, so that they will turn or swing in a plane parallel therewith.

The arms C preferably extend upwardly and then outwardly away from their pivotal connections with the frame and are connected together at their outer ends at each side of the frame by a connecting bar D which is pivotally secured thereto and extends parallel with the side of the frame. The bar D is provided at intervals throughout its length with hooks *d* which project outwardly therefrom and are adapted to engage the side rails of the bed for supporting the springs thereon.

In the drawings the supporting means at one side only of the frame A are shown, but it will be understood that similarly constructed supporting means are employed for the other or opposite side of the frame.

The connecting bar D causes the arms C at each side of the frame to turn in unison about their respective pivotal connections with the frame A and the construction is such that the arms can be swung inwardly toward the frame to a point where the hooks *d* carried by these arms lie within the vertical plane of the outer edges of the coiled springs, so that the hooks will not project beyond the same and increase the width of the bed spring when not in use. Further, in this retracted position the hooks are out of the way where they do not interfere with the handling of the spring and are not liable to become broken or bent out of shape in crating and shipping the same. As the arms are swung outwardly the connecting bar D and its hooks are moved uniformly away from the side edge of the frame and the width of the frame may thus be increased as desired, until the arms reach the limit of their outward movement when they extend parallel with the slats of the frame. The uniform movement of the arms serves to retain the connecting bar D at all times parallel with the side of the frame and in position for engagement throughout its length with the side rail of the bed when the

adjustment of the arms is completed. As these arms are arranged at each side of the frame, a considerable adjustment thereof is obtained, so that the frame can be fitted 5 to iron and wooden beds of varying width. If desired, the supporting arms and their connections can be arranged at the ends of the bed spring for engagement with the end rails of the bed, and in this case can be ad- 10 justed to fit beds of varying length.

The adjustment of the arms can be easily effected by swinging them to bring their hooks into proper position for engagement with the rails of the bed and this can be 15 done without trouble at the same time that the bed spring is being placed in position in the bed. When the hooks are once in engagement with the rails of the bed, they will securely hold the bed springs in their 20 proper position therein, and there are no parts which require to be fastened or tightened for this purpose.

The construction of the adjustable supporting means is a very simple and inexpensive one and can be applied to various 25 types of bed springs in common use. The extent of adjustment depends upon the length of the radius upon which the pivoted supporting arms turn and these arms can 30 therefore be constructed so as to give a greater or less adjustment to the bed spring, as may be desired.

I claim as my invention:

1. In a bed spring, the combination with 35 a rigid spring frame, of bars arranged sub- stantially parallel with the opposite sides of said frame and adapted to extend length- wise over and be supported by the rails of a bed, and a plurality of arms connected 40 to said frame and to said bars by vertical pivots for supporting said spring frame from the bed rails, whereby said bars can be moved horizontally toward and from said frame to suit beds of different widths and 45 are maintained parallel with the sides of said frame and said bed rails.

2. In a bed spring, the combination with 50 a rigid noncollapsible supporting frame and a plurality of upright coiled springs which overhang a side of said frame, of a plu- rality of supporting arms pivotally secured

to the side of said frame, and a rail-engag- ing member pivoted to said supporting arms, 55 said arms being free to turn on said frame about axes substantially perpendicular thereto to permit the rail-engaging mem- ber to be swung to positions in which it lies substantially within the plane of the outer edges of said upright springs and to posi- 60 tions in which it projects beyond the same, 65 said members being at all times parallel to the side of the frame, substantially as set forth.

3. In a bed spring, the combination with 65 a rigid supporting frame, of a plurality of parallel supporting arms pivotally secured at their inner ends to the frame at one side thereof to turn about axes substantially perpendicular to the frame, a connecting bar pivoted to the outer ends of said arms, 70 said arms being free to turn in unison on said frame to permit said bar to be moved toward and away from said frame, said arms being parallel to each other and said bar being parallel to said frame in all po- 75 sitions, and rail-engaging hooks carried by said bar, substantially as set forth.

4. In a bed spring, the combination of 80 a rigid frame comprising transverse slats and longitudinal connecting members, of a plurality of parallel supporting arms pivotally secured to the ends of said slats to turn about axes substantially perpendicular to said slats, said arms having intermediate 85 portions bent upwardly from said slats and outwardly projecting ends substantially parallel to said slats, and a rail-engaging bar pivoted to the outwardly projecting 90 ends of said arms, said arms being free to turn in unison on said slats to permit said rail-engaging bar to be moved toward and away from said frame, said arms being parallel to each other and said rail-engag- 95 ing bar being substantially perpendicular to said slats for all positions of said arms and bar, substantially as set forth.

Witness my hand this 16th day of June, 1911.

CHARLES HULPIAN.
